UNITED STATES PATENT OFFICE.

PARKER P. PAUL, OF CINCINNATI, OHIO, ASSIGNOR TO THE PAUL SHOE MFG. CO., OF CINCINNATI, OHIO, A CORPORATION OF OHIO.

ADJUSTABLE SLIPPER FOR UNDERTAKERS.

1,184,123.

Specification of Letters Patent. Patented May 23, 1916.

Application filed June 26, 1914. Serial No. 847,556.

To all whom it may concern:

Be it known that I, PARKER P. PAUL, a citizen of the United States, residing at the city of Cincinnati, in the county of Hamilton and State of Ohio, have invented certain new and useful Improvements in Adjustable Slippers for Undertakers, of which the following is a specification.

The object of my invention is to produce a cheap, simple and efficient slipper or shoe to be used by undertakers or funeral directors in dressing the corpse for burial. It is self adjusting rendering it capable of being placed on any sized foot, and its peculiar construction enables it to fit the foot tightly and glove like so that it will appear natural. Slippers of this character (as now in vogue) are made of one size only and consequently do not fit the foot, either as to length or breadth, and therefore do not appear natural on the feet, appearing ill shaped, wrinkled and stiff, thus marring the symmetry of the outfit; causing a great deal of worry and annoyance to the undertaker and disappointment to the family and relatives of the deceased; it being a well known fact that the family and friends desire the deceased person to appear as natural as possible. In my invention I obviate all these difficulties and objections and produce a slipper which can be placed upon any foot and it will appear natural and fit the foot properly and snugly and adapt itself to the contour or form of the foot. I need make it only of one size and out of any suitable material, soft pliable being preferred.

In the accompanying drawing, forming part of this specification, Figure (1) is a perspective view of my slipper, looking at it from the side and back thereof, the slipper being laced and Fig. (2) is a rear perspective view of the slipper, unlaced.

The slipper is composed of an upper (1), a sole (2) and a tongue (3). The upper can be of any ordinary shape and of any material as can the sole (2) and they may be united together in any suitable manner; however, they are more or less flexible and soft so the slipper can be forced to conform to the foot contour; leather being the preferred material used. The tongue (3) is connected to the sole (2) at the rear or heel end of the slipper, as shown at (4), and it

may be connected in any substantial and permanent way, preferably by being sewed in place. At the rear of the slipper the upper (1) is divided or cut open, the division reaching the sole, so that flaps (5) (5), are formed. In these flaps at their inner edges I place lacing holes (6) through which the lace string (7) passes to bind the flaps (5) (5) together. The tongue (3) is preferably made of soft leather and of the shape shown and is sewed onto the sole (2) in such a manner that the flaps (5) (5), are on the outside of said tongue (3). The tongue (3) is preferably made to extend above the top of the flaps (5) (5). This tongue can be made of any shape and be connected to the slipper in any desired manner. It will be readily apparent that the slipper can be made to fit feet of varying size and contour.

In applying to the foot, the slipper is unlaced and slipped onto the foot, the lace (7) is then pulled tight until the slipper fits properly and satisfactorily, any surplus lace string (7) may then be cut off and the heel appears in a finished and symmetrical form. In pulling the lace strings (the slipper, on account of its flexibility and shape) and consequent pulling on the flaps (5) (5), the said process of lacing and pulling pulls and forces the forward part of the upper (1) and sole (2) to conform to the width and contour of the foot, so that when laced up a perfect fit is the result. The space between the flaps (5) (5), at their meeting point on the heel, will be varied according to the size of the foot and heel to which the slipper is being applied, the tongue (3) fitting this space and covering it between the said flaps (5) (5), so that a wall of leather is always present to cover the heel of the foot. The tongue (3) also gives a finger hold in putting on the shoe, if desired and when occasion requires.

It may be stated that I form a self adjusting shoe and produce a heel therefor which may be varied in extent and size; thus I accomplish a new result, not attainable in the slippers now used for this purpose.

While I have shown and described one specific form and make of slipper illustrative of my invention, it will be readily apparent that it can be altered and modified

and I wish to be understood that these modifications will still fall within the scope of my invention.

What I claim as new and my invention, 5 and desire to secure by Letters Patent is;

A slipper for undertakers' use, having a sole and an upper, both flexible throughout, the upper at the heel part being divided from top to the sole to form flaps separated 10 from each other by a space extending to the sole, and capable of being flexed to bring their vertical edges substantially into the plane of the sole, a flexible tongue so united to the sole at the point where the vertical

edges of the flaps meet the latter that the tongue may be turned backward to occupy a position where it is entirely in the plane of the sole, and means for lacing together the vertical edges of the flaps in such manner that the slipper may be closed at the 20 rear and adjusted to closely fit various sizes of feet.

In testimony whereof I affix my signature in presence of two witnesses.

PARKER P. PAUL.
